(57) **CLAIM**

The ornamental design for a sun screen panel, as shown and described.

DESCRIPTION

FIG. 1 is a perspective view of the sun screen panel according to one embodiment;

FIG. 2 is a right side elevational view of the panel shown in FIG. 1;

FIG. 3 is a left side elevational view of the panel shown in FIG. 1;

FIG. 4 is a front elevational view of the panel shown in FIG. 1;

FIG. 5 is a rear elevational view of the panel shown in FIG. 1; FIG. 6 is a top plan view of the panel shown in FIG. 1; and, FIG. 7 is a bottom plan view of the panel shown in FIG. 1. The panel has been broken in the center to show indefinite length. The broken lines in the drawings are included for the purpose of illustrating environment and form no part of the claimed design.
